UNITED STATES PATENT OFFICE.

HENRY K. SANDELL, OF CHICAGO, ILLINOIS, ASSIGNOR TO HERBERT S. MILLS, OF CHICAGO, ILLINOIS.

WIRELESS TRANSMITTING SYSTEM.

1,391,855.

Specification of Letters Patent. Patented Sept. 27, 1921.

Application filed November 28, 1919. Serial No. 340,998.

To all whom it may concern:

Be it known that I, HENRY K. SANDELL, a citizen of the United States, residing at Chicago, in the county of Cook and State of Illinois, have invented a new and useful Improvement in Wireless Transmitting Systems, of which the following is a specification.

The present invention relates to systems for the transmission of wireless signals, and more particularly to transmitting or sending means whereby signals are transmitted by the use of undamped or continuous waves.

In accordance with the present invention an electron tube or space current device is utilized for the production of oscillating electrical impulses, which are modified by suitable means for the production of the signals which are to be transmitted. In order to produce these oscillations the input circuit of the electron tube is so arranged as to be responsive to changes in the currents in the output circuit thereof, and by its responsiveness to such changes, to produce an oscillating current in the output circuit. The signals to be transmitted are then imposed upon this oscillating circuit.

In the accompanying drawing there is shown in diagrammatic form a system embodying the present invention. In the drawing,

Figure 1 is a diagrammatic representation of the system, and

Fig. 2 illustrates the relative arrangement 35 of the loops of the system of Fig. 1.

In the drawing, the numeral 5 indicates an electron tube or space current device, for example, of the audion type, having a filament 6, a grid 7 and a plate 8, the filament 6 being heated by means of a suitable battery 9. The plate is connected by conductor 10 to the positive pole of the battery 11, and the output circuit is completed by the connection 12 to the negative pole of the battery 11, the aerial 13 shown as of the spiral or loop type, and the conductor 14 leading to the filament 6. The aerial or loop 13 is grounded by means of a suitable conductor 15, the point of connection of this 50 conductor and of the connector 14 being variable on the loop.

The input circuit of the electron tube comprises the grid 7, conductor 16, condenser 17 preferably of low capacity, conductor 18, 55 which has a variable point of contact with

the loop or aerial 19, and conductors 20 and 21 which connect at 22 with the conductor 14 leading in to the filament 6. In order to produce the desired variations in the oscillating current in the output circuit, the secondary 23 of a transformer may be connected in the series in the input circuit, the primary 24 being connected in series with the transmitter 25 and the battery 26.

The loop for the aerial 19 is rotatably mounted upon a suitable standard 27 from which it is insulated, and is placed in proximity to the loop 13 of the output circuit, as indicated in Fig. 2. Its angular position relative thereto may be varied by rotating it to any desired position.

In operation, on closing the output or plate circuit, the reaction produced upon the loop or aerial 19 in the intake circuit results in the production of oscillating currents in the output circuit, the two loops acting as a coupling for the production of this effect. By varying the angular position of the loop 19 relative to the loop 13, the conditions for most efficient operation may be readily determined. By use of the transmitter 25 or other signaling device, variations in the current in the input circuit may be produced, which are reproduced in the output circuit by which they are transmitted as impressed upon the oscillating circuit therein. It is readily apparent that the signals may be directly impressed upon the output circuit instead of upon the input circuit, but the latter method is preferred by reason of its greater efficiency.

It is furthermore apparent that the mutual reaction of the output and input circuits whereby the oscillating current in the output circuit is produced may likewise be produced by the use of other coupling devices, for example, by coils. It is furthermore to be understood that the specific details of the system herein described are not intended to be regarded as limitations upon the scope of the invention, except in so far as included in the accompanying claims.

I claim:

1. In a wireless transmitting system, an electron tube having an input and an output circuit, a loop aerial in series in the input circuit, and a loop aerial in series in the output circuit and in proximity to the first mentioned loop.

2. In a wireless transmitting system, an

electron tube having an input and an output circuit, a grounded loop aerial in series in the output circuit, a loop aerial in series in the input circuit, said loops being in proximity to each other and their relative angular positions being variable.

3. In a wireless transmitting system, an electron tube having an input and an output

circuit, a grounded loop aerial in series in the output circuit, a loop aerial in series in the input circuit, a transformer, the secondary of which is in series in the input circuit, and means for producing variations in the primary of said transformer.

HENRY K. SANDELL.
